UNITED STATES PATENT OFFICE

2,104,005

CONTAINER

Charolette A. Arnesen, Chicago, Ill.

Application September 2, 1930, Serial No. 479,164
Renewed May 6, 1936

12 Claims. (Cl. 220—53)

The invention relates generally to containers and more particularly to metallic containers used for food and having an opening element which is ripped or torn from its closing relation to the parts of the container, usually by means of a key so as to separate the container into two parts and thereby permit opening thereof.

In opening containers of this character it has been found that small splinters of metal are often formed along the two torn edges of the parts which are separated by ripping of the opening element from its normal position, and that these splinters sometimes fall into the food packed in the container. The presence of such metal in the food is obviously injurious to the health of the consumer and the primary object of the present invention is to provide a new and improved container of this character embodying means to prevent the metal particles from reaching the food within the container.

Another object is to provide a container of this character embodying means operable to guide the opening element as it is ripped from its normal position in such a manner as to prevent breaking of the element or improper tearing of the wall of the container.

Other objects and advantages will become apparent from the following description taken in connection with the accompanying drawing, in which:

Figure 1 is a fragmental perspective view showing one end of a container embodying one form of the invention.

Fig. 2 is an enlarged fragmental section showing the container illustrated in Fig. 1.

Fig. 3 is a fragmental sectional view taken along the line 3—3 of Fig. 2.

Fig. 4 is a view similar to Fig. 2 and illustrating another embodiment of the invention.

Fig. 5 is a plan view of the container shown in Fig. 4.

For purposes of disclosure, two embodiments of the invention are illustrated in the drawing and will hereinafter be described in detail as applied to a container having a particular type of opening element formed as an integral part of the auxiliary wall which surrounds the main or inner wall of the container, but it is to be understood that this disclosure is not intended as a limitation of the invention to this particular type of opening element nor to this particular type of container, it being contemplated that various changes might be made by those skilled in the art without departing from the spirit and scope

of the invention as defined by the appended claims.

In the form shown in Figs. 1 to 3 as well as in the form shown in Figs. 4 and 5, the invention is embodied in a container having an annular side wall 10 closed in a conventional manner at its lower end by bottom wall 11 (Fig. 3) and having an open upper end defined by the upper edge 12 of the side wall 10. Extending across and closing the upper end of the container is a cover 13 which carries an annular flange, seamed thereto at 13a and designated generally by the numeral 14, adapted to surround the upper portion of the side wall 10 and to be secured thereto by soldering the lower edge 15 of the flange 14 to 15 the wall 10 so as to seal the container.

As illustrated herein, the opening element is of the type which is integrally formed on the flange 14 and comprises an annular strip 16 of the flange which is adapted to be ripped from its position to separate the flange into two parts and thereby permit removal of the cover 13. In order to insure proper operation of the opening element, it is preferably positioned between a pair of parallel outwardly projecting beads 17 formed in 25 the flange 14 so as to connect directly to the beads. The junctions of the two edges of the strip 16 with the adjacent beads 17 are quite sharp or angular as shown in Figs. 2 and 4 of the drawing and are structurally weakened as 30 indicated at 18 so as to facilitate the ripping of the strip 16 from its connecting relation with the two beads 17. By grasping a lug or flap 19 conventionally connected to the strip 16, the strip may be torn progressively about the container. This is preferably accomplished by a longitudinally slotted key 20 (Fig. 1) which may be engaged with the lug 19 and rotated to roll the strip about the key as shown in Fig. 1.

As the strip 16 is ripped from its position between the two beads 17, it is guided by contact with the sides of the beads whereby to insure proper formation of roll about the key. The efficiency of the beads 17 as guides is materially increased by forming the sides adjacent the strip 40 16 substantially perpendicular to the strip. By this construction the strip is engaged and guided at a substantial distance from the point at which it is being torn from the beads. The beads 17 also serve to definitely limit the width of the portion 45 50 which is torn from the flange.

When the opening element 16 is carried by an auxiliary or outer wall such as the flange 14 herein shown, the fine splinters of metal which are formed along the adjacent edges (that is, the 55

torn edges of the beads 17 are liable to be dropped into the food in the container as the cover 13 is lifted upwardly and removed from the can. This is especially true in case the torn edge 5 of the upper bead 17 strikes the upper edge 12 of the side wall as the cover is removed.

In the embodiment illustrated in Figs. 1 to 3 of the drawing, this undesirable result is avoided by means acting during the tearing of the strip 10 16 to wipe along the torn edges of the beads 17 so as to remove all of the minute splinters of metal which may be left upon these torn edges. This means preferably comprises a strip 21 (Figs. 2 and 3) of tough flexible material such as paper 15 positioned between the flange 14 and the wall 10. The paper strip 21 is of slightly greater width than the opening element 16 and extends laterally in both directions therefrom (Fig. 2) and its ends are overlapped as shown in Fig. 3, so 20 that the outer end of the paper strip 21 projects in the same direction as the lug 19 of the opening element.

In order that the paper strip 21 will act automatically to wipe the edges of the beads 17 as the 25 opening operation progresses, the outer end of the strip is fastened to the opening element 16 at a point 22 located on that part of the opening element which is to be first removed. This may be accomplished by means of a suitable adhesive. 30 With this construction the laterally projecting edges of the paper strip 21 are bent as the strip 21 is drawn bodily through the opening between the two beads 17 and the bent edges of the paper will wipe along the torn edges of the beads 17 and 35 will remove all metal which may be loosely attached thereto. Proper wiping of the torn edges of the opening is insured due to the action of the two beads 17 in definitely limiting the opening to a width substantially less than that of the 40 paper strip 21. Since the torn edges of the beads 17 have been thoroughly wiped by the strip 17, the cover 13 may then be removed without danger of having the metal particles fall from the cover into the food packed in the container.

45 In the form shown in Figs. 4 and 5, the food within the container is protected by a paper cap designated generally as 23, Fig. 4. The cap 23 is of inverted cup-shaped form with its flat portion 24 extending across the open end of the container within the cover 13 and the side 25 of the cap 23 extending downwardly between the flange 14 and the side wall 10. Preferably the lower edge of the side 25 of the cap extends beyond the lower bead 17 and is gripped tightly between the 50 wall 18 and the lower edge 15 of the flange 14 as shown in Fig. 4.

Thus after the opening element 16 has been removed, the cap 23 will be held in place while the cover 13 and the attached portion of the flange 60 14 are removed, with the result that any metal particles dropping from the torn edge of the upper bead 17 will be excluded from the interior of the container. The flat portion 24 of the paper cap may then be torn from the center as indicated by the dotted lines 26 (Fig. 5) and drawn 65 downwardly along the sides of the container so as to overlie the torn edge of the lower bead 17 as the food is poured or otherwise removed from the container.

70 It will be noted that the protecting element in both forms of the invention is of such a character that it is fixed in its position as an incident to the securing of the cover on the container and that by reason of this fact the invention may be 75 readily and economically utilized with the type of

can making and sealing machinery now in use. If instead of employing a tearing strip it is desired to provide for opening the container by a cutter, the upper bead 17 may be used to advantage with a suitable cutter such as that shown in my co-pending application No. 706,246 filed January 11, 1934. It will be seen that this upper bead provides an annular unoccupied clearance space around the container for receiving the edge of the cutter in the operation of severing the metal, and that this space is closed on its inner side to prevent the entrance of metallic particles formed as an incident to the cutting operation.

I claim as my invention:

1. In a metallic container having a side wall, a 15 cover, a flange secured to said cover and extending along the outer surface of the side wall, means securing the edge of said flange to said side wall, said flange having an elongated strip thereof adapted to be ripped therefrom to sever said 20 flange between said cover and said edge of the flange, and means positioned between said flange and said side wall operable as said strip is ripped from the flange to wipe the edges of the opening 25 thus formed.

2. In a metallic container having a side wall, a 30 cover, a flange secured to said cover and extending along the side of the side wall, means securing the edge of said flange to said side wall, said flange having an elongated strip thereof adapted 35 to be ripped therefrom to sever said flange between said cover and said edge of the flange, and means positioned between said flange and said side wall operable as said strip is ripped from the flange to wipe the torn edge of the flange 40 which remains attached to the cover whereby to remove loose metal therefrom.

3. In a metallic container having a side wall, a 45 cover, a flange secured to said cover and extending along the outside of the side wall, means securing the edge of said flange to said side wall, said flange having an elongated strip thereof adapted to be ripped therefrom to sever said 50 flange between said cover and said edge of the flange, and means positioned between said flange and said side wall and adapted to be drawn through the opening formed in the flange to wipe the torn edges and remove loose metal therefrom.

4. In a metallic container having a side wall, a 55 cover, a flange secured to said cover and extending along the outside of the side wall, means securing the edge of said flange to said side wall, said flange having an elongated strip thereof adapted 60 to be ripped therefrom to sever said flange between said cover and said edge of the flange, and means enclosed by the cover and operable to exclude from the food contained therein the particles of metal formed in the opening of the container.

5. In a metallic container having a side wall, a 65 cover, a flange secured to said cover and extending along the side of the side wall, means securing the edge of said flange to said side wall, said flange having an elongated strip thereof adapted to be ripped therefrom to sever said flange between said cover and said edge of the flange, and means comprising a sheet of frangible material 70 enclosed by the cover and arranged to be secured in place as an incident to the fastening of the flange to the side walls and operable to exclude metal particles from the food.

6. A metallic container having a wall with an elongated opening element forming a part of said wall, said element being adapted to be ripped from said wall to open said container, an elong- 75

gated strip of tough paper positioned within said wall and extending longitudinally of said element, said strip being of greater width than said element, and means securing said strip to said element whereby to cause said strip to be drawn through the opening formed in said wall as the opening element is ripped from its position.

5 7. A sealed metallic container having a wall with an elongated opening element forming a part of the wall, said element being adapted to be ripped from said wall to separate said container into two parts, and a piece of paper positioned within said container wall and adapted to be drawn through the opening in said wall 10 formed by ripping of said element and to wipe the edge of said opening to remove loose metal therefrom.

8. A sealed container comprising metallic side and bottom walls, a metallic cover having a flange 20 adapted to be slipped over the upper end of said side walls, said flange having an opening element embodied therein for separating the flange between the cover and the edge of said flange, means sealing the container and securing the 25 edge of said flange to said side walls, a paper cap enclosed by the cover and extending across and closing the upper end of said side walls, said cap projecting into the space between said flange and said side walls and encircling said side walls.

30 9. A sealed metallic container having end and side wall, said side wall coating with one end wall to form a cover and embodying an opening element adapted to be ripped from the side wall to permit removal of the end wall, and a paper cap 35 enclosed by the cover in overlying relation to said end wall and extending away from said end wall and along said side wall beyond said opening element, and means securing said cap to said side wall along a line lying between said opening element and the other end wall.

40 10. A container having an annular side wall and a cover having a flange with a pair of spaced parallel beads formed therein so as to extend

around said container and project outwardly from said wall, the portion of said wall lying between said beads constituting an opening element adapted to be ripped from its connecting relation with the two beads, a lug connected to 5 said opening element and positioned on the outer side of the container, an elongated piece of paper enclosed by the cover and extending longitudinally along said opening element, said paper being of greater width than said opening element 10 and extending laterally beyond both side edges of said element, and means connecting one end of said piece of paper to said opening element to cause progressive withdrawal of said paper from the container as the opening element is 15 ripped from its normal position.

11. A sheet metal container having an annular side wall, a cover having an annular flange extending along the outer side of said side wall and having its peripheral edge secured to said side wall, said cover being adapted to be ruptured to sever the cover at a point within said peripheral edge of the flange to permit removal of the cover, and means comprising a sheet of readily frangible 25 material such as paper enclosed by the cover and covering the open end of the container when the cover is removed whereby to exclude any particles of metal formed in the opening of the container by the removal of the cover.

12. A container having a sheet metal side wall, 30 a cover of sheet metal having a peripheral edge portion permanently secured to the side wall and an annular tearing strip adapted to be ripped from the cover to open the container, and a sheet of readily frangible material such as paper 35 having a peripheral edge portion fastened between the side wall of the container and said peripheral edge portion of the cover, said sheet serving to maintain the container closed so as to exclude any particles of metal formed in the 40 opening of the container by the removal of said strip.
